FEEDING MECHANISM

Ludger Guibault, Montreal, Quebec, Canada, assignee to T. P. Gelinas, Montreal, Quebec, Canada

Application October 29, 1934, Serial No. 759,476

6 Claims. (Cl. 271—32)

The present invention pertains to a novel printing mechanism designed primarily for cancelling stamps on envelopes and post cards, but also useful for other small printing jobs.

5 The principal object of the invention is to provide a simple and inexpensive device of this character which is positive in its operation and which requires very little attention. The invention resides primarily in the means for feeding 10 the work to the printing roll. This mechanism embodies a pair of pistons, one within the other, the outer piston being slideable within a fixed outside cylinder. From the outer piston extends 15 a nozzle or nipple through a slot in the cylinder, and this nipple carries a suction cup adapted to engage the work, one sheet at a time, and deliver 20 it to the printing roll.

A suction is created in the outer piston and 25 the nipple by the action of the inner piston by reason of mechanism adapted to move both pistons simultaneously in the same direction to and from the printing roll, while moving the inner piston at a higher speed than the outer piston, thereby rarefying a closed volume in the outer piston during the stroke towards the printing 30 roll.

The invention is fully disclosed by way of example in the following description and in the accompanying drawing in which

35 Figure 1 is a plan section of the machine, and Figure 2 is a vertical section thereof.

Reference to these views will now be made by use of like characters which are employed to designate corresponding parts throughout.

40 In Figure 1 the numeral 1 designates in general the fixed frame construction on which the machine is built. To this structure is secured a cylinder 2 by means of lugs 3 and bolts 4.

Embodied in the fixed structure of the machine 45 is a vertical plate 5 having a slot 6 as shown in Figure 1, for a purpose which will presently appear. There is another vertical plate 7 arranged vertically at a right angle to the plate 5. One of the vertical edges 8 of the plate 7 is spaced slightly from the plane of the plate 5 at a distance equal to the thickness of the envelopes or other articles operated upon by the machine.

The cylinder 2 contains a piston 9 in the form 50 of a hollow slideable cylinder having a nozzle or nipple 10 extending therefrom through a slot 11 in the cylinder 2. Adjacent to the slot 11 is the previously mentioned slot 6 in the plate 5, and the latter slot receives the end of the nipple 10. On this end is fitted a suction cup 12

for picking up singly the articles placed against the wall 5 as will presently appear.

In the frame of the machine is journaled an operating shaft 13 which is driven in any suitable manner. This shaft carries a pair of cams 14 and 15, the former being joined by a link 16 to the piston 9 for reciprocating the same in the cylinder 2. This piston 9 contains another piston 17 which is driven by the cam 15 through a link or connecting rod 18.

Another shaft 19 parallel to the shaft 13 carries an inking or printing roll 20, and the two shafts are joined by sprocket wheels and a chain 21 as shown in Figure 2. Adjacent to the roll 20 is a pressure roll 22 spaced slightly therefrom at 15 a suitable distance for receiving articles that are passed across the edge 8 of partition 7.

In the operation of the device a stack of envelopes or sheets is placed vertically and edge-wise on a table 23 embodied in the fixed structure of the machine. The stack is pressed toward the vertical wall 5 and fitted endwise against the vertical wall 7. As the shaft 13 turns, the piston 9 is oscillated in the cylinder 2, and the piston 17 is oscillated within the piston 9 in the same direction and at a greater speed as may be seen by the position of the cams 14 and 15 in Figure 2 and by the fact that the cam 15 is larger than the cam 14. Due to the greater speed of the piston 17, a suction is created in 30 the piston 9 and nipple 10 on the movement towards the roll 20, whereby the nearest envelope or sheet 24 is drawn into contact with the suction cup 12 and held thereby. The simultaneous movement of the piston 9 and nipple 10 carries 35 the member 24 across the edge 8, which is properly positioned for this purpose as previously described, and between the printing roll 20 and the pressure roller 22.

The roll 20 may be adapted for cancelling 40 postage stamps, in which case the envelopes or post cards are preferably so mounted on the table 23 that the stamps are nearer the wall 7. Obviously, the roll 20 may be adapted for various kinds of printing, and the roller 22 is at all times positioned to exert the proper pressure on the sheet in the direction toward the roll 20.

Although a specific embodiment of the invention has been illustrated and described, it will be understood that various alterations in the details 50 of construction may be made without departing from the scope of the invention, as indicated by the appended claims.

What I claim is:—

1. In a printing machine, a fixed wall for sur- 55

- face contact with the articles to be printed, a fixed cylinder near said wall, said wall and cylinder having co-extensive slots adjacent to each other, a hollow piston in said cylinder, a nipple extending from said piston into said slots, another piston slidable within the first piston, a printing roll, and means for oscillating said pistons at unequal speeds in the same direction towards and away from said printing roll, the second piston traveling faster than the first towards said roll, whereby to create a suction in said nipple while traveling towards said roll. 5
2. In a printing machine, a fixed wall for surface contact with the articles to be printed, a fixed cylinder near said wall, said wall and cylinder having co-extensive slots adjacent to each other, a hollow piston in said cylinder, a nipple extending from said piston into said slots, another piston slidable within the first piston, a printing roll, said wall being substantially tangent to said roll, another wall perpendicular to the first wall and spaced slightly from the plane of the first wall, and means for oscillating said pistons at unequal speeds in the same direction towards and away from said printing roll, the second piston traveling faster than the first towards said roll, whereby to create a suction in said nipple while traveling towards said roll. 10
3. In a printing machine, a fixed wall for surface contact with the articles to be printed, a fixed cylinder near said wall, said wall and cylinder having co-extensive slots adjacent to each other, a hollow piston in said cylinder, a nipple extending from said piston into said slots, another piston slidable within the first piston, a printing roll, a rotatable shaft, unequal cams carried by said shaft and connected respectively to said pistons and so related as to move said pistons simultaneously in the same direction to and from said roll, the second piston moving faster than the first piston towards said roll, whereby to create a suction in said nipple while moving towards said roll. 15
4. In a printing machine, a fixed wall for surface contact with the articles to be printed, a fixed cylinder near said wall, said wall and cylinder having co-extensive slots adjacent to each other, a hollow piston in said cylinder, a nipple extending from said piston into said slots, another piston slidable within the first piston, a printing roll, said wall being substantially tangent to said roll, another wall perpendicular to the first wall and spaced slightly from the plane of the first wall, a rotatable shaft, unequal cams carried by said shaft and connected respectively to said pistons and so related as to move said pistons simultaneously in the same direction to and from said roll, the second piston moving faster than the first piston towards said roll, whereby to create a suction in said nipple while moving towards said roll. 20
5. In a printing machine, a fixed cylinder having a slot in its wall, a hollow piston in said cylinder, a nipple extending from said piston into said slot, a printing roll, means for oscillating said piston to and from said roll, means for producing suction in said piston while traveling towards said roll, and suction-operated holding means for engaging the articles to be printed. 25
6. In a printing machine, a fixed wall for surface contact with the articles to be printed, a fixed cylinder near said wall, said wall and cylinder having co-extensive slots adjacent to each other, a hollow piston in said cylinder, a nipple extending from said piston into said slots, a printing roll, means for oscillating said piston to and from said roll, means for producing suction in said piston while traveling towards said roll, and suction-operated holding means for engaging the articles to be printed. 30
